GRIDWORK FOR AIR HEATERS.

Application filed June 7, 1926, Serial No. 114,284, and in Germany April 3, 1926.

This invention relates to improvements in air heaters, especially used in connection with the blast furnaces, and has particular reference to the gridwork construction for such heaters.

Hitherto the gridwork of an air heater for blast furnaces was constructed of rectangular, hexagonal and substantially round shafts of the same cross section throughout the 10 whole height of the heater.

In order to obtain large surfaces square and rectangular shafts have been constructed with undulating surfaces.

By means of the experiments carried out 15 at the Charlottenhütte (Charlotten mine)—published under No. 82 of the Wärmestelle (Heat Department) Düsseldorf—it has been proven, on the basis of technical investigations, that the grid construction of the grid-work with square, rectangular and other 20 shafts of the same cross section is erroneous from the standpoint of the heat absorbing qualities thereof.

In recent times so-called roll or spiral 25 stones of various sizes have been used in place of the above mentioned shafts for obtaining a larger heat absorbing surface. In the past, air heaters were operated with unpurified or, at best, with preliminarily purified blast furnace gas. With unpurified gas a cleaning 30 of the shaft was frequently necessary, but even when using preliminarily purified or purified gas an inspection and cleaning of the gridwork was necessary from time to time. 35 This has been effected by illuminating the separate shafts of the gridwork and cleaning the same with brushes.

The use of roll and spiral stones prevents such cleaning. If after a long period of time 40 a stoppage or clogging with dust or a deformation takes place at one point of the roll or spiral stones, the efficiency of the heater is decreased without it being possible by examination of the interior to ascertain the 45 cause of the low efficiency. It is therefore necessary to remove the gridwork.

In order to eliminate all the disadvantages 50 of the gridwork constructions hitherto known, the present invention has for its object to provide a gridwork wherein, at the points of higher temperature, there are provided large cross sections with small surfaces and thick walls, and at the points of lower temperature there are provided smaller cross 55 sections with larger surfaces and thinner

walls. This construction produces a thoroughly solid gridwork which is capable of withstanding explosions which may occur in air heaters.

Another object is the provision of a grid-work which can be illuminated and cleaned easily by the method and in the manner hitherto employed.

Another object resides in providing large surfaces by means of which considerable 65 economy is effected due to the fact that the heaters can be built considerably lower in height.

In accordance with the above objects, stones of the simplest construction are used 70 which can be cheaply produced and therefore new air heaters may be constructed at about 50% reduction in cost below that of heaters heretofore used. The economies reside in the lower height of the construction 75 and, in addition, the efficiency of these new air heaters is considerably higher.

The same economies are effected in the reconstruction of old air heaters, as by the reconstruction the existing air heaters can be 80 made lower. In spite of this it is possible to increase the stone surface considerably and to improve the efficiency by smaller losses in exhaust gases and reduction in radiation losses.

In the drawing there is shown by way of example the gridwork of an air heater constructed in accordance with the invention. It will be understood that the gridwork for 85 regenerators and the like can be carried out in a similar manner.

Figures 1, 2 and 3 are fragmentary plan views of the gridwork employed in different zones of the heater.

Figure 4 is a partial view of the interior 95 of the heater.

In the form of construction shown, the interior of the body of the air heater (Figure 4) is divided into zones A, B, C. The wide gridwork *a* (Figure 1) fills the upper zone A. Under the gridwork *a*, in the zone B, there is then disposed the gridwork *b* (Figure 2) and underneath this the gridwork *c* (Figure 3) in the zone C.

The gridwork is so assembled that the combined area of four openings of the gridwork *c* is always equal to two corresponding openings of the gridwork *b* and one opening of the gridwork *a*.

In this manner the cleaning with brushes 110

and the illumination can be effected from a in the customary manner and without difficulty.

Having now particularly described and ascertained the nature of our said invention and in what manner the same is to be performed, we declare that what we claim is:

1. In an air heater for blast furnaces, a body divided into zones all of which are in superposed relation, and a gridwork in each zone and including heat absorbing plates, the plates of the gridwork in the zone of the highest temperature having large cross sections and small surfaces, and those in zones of lower temperatures having smaller cross sections and larger surfaces.

2. In an air heater for blast furnaces, a body divided only horizontally into different temperature zones, and a gridwork in each zone including heat absorbing plates the cross sectional areas of which vary in the

different zones directly with the temperatures therein, while the surface areas of which in the different zones vary indirectly as the temperatures.

3. In an air heater for blast furnaces, a body divided into different temperature zones, and a gridwork arranged in a single vertical block and including a plurality of sections each located in one of said zones and including plates forming openings therebetween, the area of an opening in the gridwork in the zone of highest temperature being equal to the combined areas of two openings in the gridwork in the zone of next lower temperature, and also equal to the combined areas of four openings in the gridwork in the zone of the next lower temperature.

In testimony whereof we have signed our names to this specification.

HUGO KLEIN.
PAUL KUHN.
